UNITED STATES PATENT OFFICE.

CLARK V. McCARLEY, OF TOLEDO, OHIO.

DEVICE FOR FEEDING MOIST AIR AND STEAM TO CARBURETORS.

Application filed May 9, 1921. Serial No. 467,865.

To all whom it may concern:

Be it known that I, CLARK V. McCARLEY, a citizen of the United States of America, residing at Toledo, in the county of Lucas, 5 and State of Ohio, have invented certain new and useful Improvements in Devices for Feeding Moist Air and Steam to Carburetors, of which the following is a specification.

10 My present invention relates generally to devices for feeding moist air and steam to the carburetors of internal combustion engines and is more particularly a device of this character applied to and utilized in connection with the air heating stove as it is commonly known which in connection with most internal combustion engines is clamped or otherwise secured to embrace, either partly or wholly, the engine exhaust pipe. 15 The object of my present invention is to provide simple inexpensive means whereby steam may be fed with the air to the carburetor, including simple effective and readily controlled means preventing the flow of moist air to the carburetor when the engine is stopped.

20 In the accompanying drawing which illustrates my present invention and forms a part of this specification,

25 Figure 1 is a side view of an internal combustion engine, partly in section, showing the practical application of my invention,

Figure 2 is a longitudinal section through the valve fitting,

30 Figure 3 is a detail cross section through the exhaust pipe and fluid container taken on the vertical line of its fluid connection,

Figure 4 is a partial side view of the exhaust pipe with the fluid container thereon,

35 Figure 5 is a cross section through the exhaust pipe adjacent to one end of the air heating stove,

Figure 6 is a side view thereof, and

40 Figure 7 is a vertical transverse section taken on line 7-7 of Figure 6.

Referring now to these figures I have shown in Figure 1 an intake manifold 10 and exhaust pipe 11 of an internal combustion engine for instance as used in a vehicle 45 of which the dash appears at 12 and the instrument board at 13, the latter having a control button 14 for a purpose to be presently described, which may if desired be coupled in any suitable manner with the control of the ignition.

A fluid reservoir 15 is preferably mounted

upon the inner forward surface of the instrument board 13 where it can be conveniently reached for filling purposes from time to time, and from this reservoir a feed pipe 60 16 leads forwardly through the dash and is preferably provided with a cutoff valve 17 adjacent to the reservoir 15 and thus within convenient reach of the operator.

The lower forward end of the feed pipe 65 16 communicates by means of a lateral nipple 18 with a fluid container 19 secured in any suitable manner upon one side of a portion of the exhaust pipe 11 and opening upwardly as particularly seen in Figures 3 and 70 15. This fluid container is preferably filled with a non-combustible absorbent material as for instance wool asbestos and it is obvious that with the valve 17 open feed by gravity of water from the reservoir 15 is provided for to the container 20 so that when the exhaust pipe 11 becomes heated in the normal action of the engine steam or water vapor can freely rise from the upper open end of the container 19.

80 The carburetor shown at 21 in Figure 1 has the usual air intake nipple 22 which in accordance with my invention is connected by a valve fitting 23 with one end of a pipe 24 having at its opposite end a downwardly opening generally rectangular air heating stove 25 partly embracing the exhaust pipe 11 and also enclosing at one side the fluid container 20. Stove 25 may be secured in any suitable manner to the exhaust pipe 11 85 90 as for instance by hook bolts 26.

95 The valve fitting 23 has a depending outlet 27 normally covered by a valve piece 28 which swings on a pivot pin 29 so that it may be shifted from a horizontal position closing the outlet 27 to a vertical position against an internal valve seating rib 30 to close the air passage to the carburetor at a point between the carburetor and the outlet 27, and at the same time place this outlet 27 100 in communication with the pipe 24 leading from the air heating stove.

105 The pivot pin 29 has an external arm 31 seen in Figure 1, connected by a rod 32 with one arm of a bell crank 33, the other arm of which is connected by a rod 34 whose rear end projects rearwardly through a vertical slotted opening in the dash 12. This rear end of rod 34 is adjustably clamped at 35 to one slotted end of a lever 36 fulcrumed upon the dash 12, and to the other end of which is pivotally connected the forward end of a

rod 37 connected at its rear end with the control button 14 before described. The adjustable clamp 35 provides for the adjustment of the throw of rod 34 depending upon the proportion of movement available at the control button 14 in respect to the required swinging movement of the valve piece 28, and for adjusting purposes the rod 34 is preferably in section connected by a 10 turnbuckle or similar adjustable coupling as at 38.

Thus at the start of operations the button 14 is pulled upwardly from the instrument board 13 which throws the valve piece 28 15 from the vertical position shown in dotted lines in Figure 1 to the horizontal working position shown in full lines in Figure 2 so that when the engine is started its suction draws air into the carburetor 21 through the 20 stove 25, which air is slightly moistened by virtue of its passage over the upper open end of the fluid container 19.

As the engine warms up and the exhaust pipe 11 becomes heated, steam or vapor will 25 be generated within the fluid container 19 and will rise therefrom into the stove 25 to join with the air and pass to the carburetor. When the engine is again shut off control button 14 is pressed inwardly to shift the 30 valve 28 back to the position of Figure 1 and thus prevent passage of moist air and steam so as to avoid the possibility of condensing within the carburetor, the steam subsequently rising from the fluid container 35 until the exhaust pipe 11 cools, finding a free outlet through the outlet extension 27 of the valve fitting.

I am aware that it is well known that the feeding of steam and moist air as a part of the combustible fuel of an internal combustion engine will retard the formation of carbon within the engine cylinders and in this way tend to maintain uniform efficiency of the motor as well as to effect economy in fuel.

I am not aware however that this has been accomplished in the manner proposed by my present invention nor under control as shown to which my invention is efficiently adapted.

I claim:

An engine exhaust pipe having a container adapted to hold absorbent material fixed to its side and opening upwardly at a point below the top of the pipe, a fluid supply pipe leading into the said container at one side, a stove in the form of a downwardly opening air container having end walls cut away to seat on the exhaust pipe and having side walls depending at the sides of said exhaust pipe, one of which side walls extends along said container in spaced relation thereto and has a vertical slot receiving said fluid supply pipe, hook bolts depending from the top of said stove and embracing the exhaust pipe to detachably hold the stove in position whereby the stove may be readily removed from the exhaust pipe and said container without wholly detaching the said bolts.

In testimony whereof I have affixed my signature.

CLARK V. McCARLEY.
